US00D979148S

(12) **United States Design Patent** (10) **Patent No.:** **US D979,148 S**
Rogers et al. (45) **Date of Patent:** **** Feb. 21, 2023**

(54) **WATER RESCUE EXTRACTION DEVICE**

(71) Applicants: **Michael Scott Rogers**, Rockledge, FL (US); **Matt Haynes**, Birmingham, AL (US)

(72) Inventors: **Michael Scott Rogers**, Rockledge, FL (US); **Matt Haynes**, Birmingham, AL (US)

(**) Term: **15 Years**

(21) Appl. No.: **29/752,066**

(22) Filed: **Sep. 24, 2020**

(51) LOC (14) Cl. **02-99**

(52) U.S. Cl.

USPC **D29/124**

(57) **CLAIM**

The ornamental design for a water rescue extraction device, as shown and described.

DESCRIPTION

FIG. 1 is a top view of the water rescue extraction device showing our new design;

FIG. 2 is a bottom view thereof;

FIG. 3 is a side view thereof;

FIG. 4 is a front view thereof;

FIG. 5 is a bottom perspective view thereof;

FIG. 6 is a top perspective view thereof;

FIG. 7 is a back view thereof;

FIG. 8 is a back closed view thereof; and,

FIG. 9 is a front closed view thereof.

1 Claim, 9 Drawing Sheets
